Specification for Design.

Patented Jan. 2, 1917.

Application filed October 6, 1916. Serial No. 124,198. Term of patent 3½ years.

To all whom it may concern:

Be it known that I, TOSHIO SOGA, a subject of the Emperor of Japan, residing in the borough of Brooklyn, county of Kings, city and State of New York, have invented a new, original, and ornamental Design for an Animal Figure, of which the following is a specification, reference being had to the accompanying drawing, forming part hereof.

Figure 1 is a front elevation and Fig. 2

is a rear elevation of an animal figure, showing my new design.

The design consists of the figure of a cat in sitting posture with one paw in raised position, there being a collar or band around the neck of the cat.

I claim:

The ornamental design for an animal figure, as shown and described.

TOSHIO SOGA.
